FLUID FLOW COMPENSATING DEVICE

Gerrit Evert Euwe, Vlaardingen, Netherlands, assignor to Lever Brothers Company, New York, N.Y., a corporation of Maine

Filed Oct. 28, 1955, Ser. No. 543,426

Claims priority, application Netherlands Oct. 29, 1954

10 Claims. (Cl. 99—244)

This invention relates to compensating devices and more particularly to compensating devices for coupling continuously operating and intermittently operating stages of a fluid system.

Devices are known, such as disclosed in U.S. Patent No. 2,474,136, for example, for coupling continuous and intermittent flow stages in systems for accommodating fluid substances, particularly incompressible substances, such as margarine, or the like. While the known devices are generally satisfactory for systems in which the throughput is substantially constant over a given time interval, they make no satisfactory provision for conditions such as an occasional temporary speed up or slow down in either the continuous flow or the intermittent flow stage. Using the principle of the system of said patent, for example, excess flow can become separated from the continuous throughput which follows.

It is an object of the present invention, therefore, to provide a compensating coupling unit for accommodating random variations in the flow characteristics of a system in which a continuous flow device and an intermittent flow device are used in tandem.

Another object of the invention is to provide improved apparatus for use in the production or transmission of flowable substances such for example as margarine.

In accordance with the present invention, there is provided a coupling apparatus for accommodating fluid flow including a chamber for receiving the flow and a variable stroke piston displaceable in either direction to compensate over a certain time interval for a wide range of ratios between inflow and outflow. To this end, the fluid substance can be introduced into the chamber through the piston itself and the piston biased to urge the fluid out of the chamber under substantially uniform pressure, but at the same time, capable of yielding to enlarge the chamber size at such times as the outflow is temporarily below that of the inflow.

Representative embodiments of the invention from which the above and various other features and objects will be readily understood are described below having reference to the accompanying drawing in which:

Figure 1 is a schematic diagram of a system useful in the manufacture of a flowable substance such as margarine;

Figure 2 is a view in longitudinal section of the compensating coupling unit between the input and output ends of the system of Figure 1; and

Figure 3 is a view in longitudinal section of a modified form of compensating unit.

Referring to the drawing and to the schematic of Figure 1 in particular, the invention is illustrated as embodied in a system useful in the manufacture of a fluid or flowable plastic substance such as margarine including a continuous flow input stage 10, which can take the form, for example, of a conventional Votator such as described in "Industrial Oil and Fat Products," 1945, pages 702-708. As described in this book, the term "Votator" designates a device for rapid chilling of fluid substances comprising

2

one or more thin walled tubes arranged to be surrounded by a chilling medium, such as evaporating liquid ammonia. The tubes are provided with internal rotating blades which remove the thin film of chilled material from their walls. The system of the invention also includes an intermittent flow output stage 11 which can take the form of a packaging or metering device, such as disclosed in U.S. Patent No. 2,474,136, wherein a packaging device intermittently accepts uniform quantities of viscous substance from a conduit connected to a chilling unit, such as a Votator, and a coupling stage 12 for accommodating the different flow characteristics of the two stages 10 and 11 in such a manner that the system can be operated continuously despite random variations in flow rate in either stage.

Referring now to Figure 2, the coupling stage 12 is illustrated in one of its embodiments as comprising a chamber or cylinder 13 which can be coupled to a crystallizing body 14 coupled in turn to a mouth piece 15 adapted to be connected for example to the output stage 11. Received in the cylinder 13 is a piston assembly indicated generally by the numeral 16 movable randomly to and fro under the control of yieldable actuating means which can take the form of a second piston 17 working in a cylinder 18 and connected to move with the piston assembly 16 by a hollow rod 19.

The cylinder 18 can, if desired, be rigidly connected to the cylinder 13 by suitable means such for example as an open distance piece 20. The right hand end, as viewed in the drawing, of the cylinder 18 is closed by a cap piece 21 centrally apertured to receive and carry a fixed pipe 22 extending inwardly therefrom cantilever fashion to be received coaxially within the hollow rod 19, first passing slidably through an axial opening 23 and sealing gland 24 in the piston 17. The free or inner end of the fixed pipe 22 carries suitable packing rings 25 to engage the inner wall of the pipe 19 in a fluid tight seal affording relative sliding or telescoping motion. The outer end of the pipe 22 is adapted to be connected to the input stage 10 to receive for example a continuous flow of margarine, which it conveys into the hollow rod 19.

The piston assembly 16 to which the rod 19 is connected, is formed with a central opening 26 communicating with the interior of the rod 19 to pass the fluid or plastic substance into the cylinder 13 on the left hand or front side of the piston assembly 16. In order to distribute the plastic substance evenly over the cross section of the cylinder 13, the piston assembly 16 can be formed with a conical recess 27 in which is fitted a matching conical face 28 spaced therefrom as by distance pins 29 and secured as by bolts 30 to define a toroidal space 31 to convey the material radially outwardly in all directions toward the inner wall of the cylinder 13. Joined to the conical face 28 in opposed relation with respect thereto is an outer conical face 32 forming the working side of the piston and over which the material emerging from the toroidal space 31 passes. Sealing means 33 are provided to prevent leakage between the cylinder 13 and the atmosphere around the piston assembly 16.

Possible accumulations over a long interval of material leaking around the piston assembly 16 can be removed by means of a suitable outlet 34. Similarly, any material which might leak around the sealing rings 25 at the free end of the fixed pipe 22 can be taken off through an opening 34a in the hollow rod 19.

The piston 17 is adapted to be driven to the left in its cylinder 18 by means of fluid pressure, either pneumatic or hydraulic introduced through an opening 35 in the end piece 21. As seen in the schematic diagram of Figure 1, this fluid can derive from a suitable source 36 through valve means 37 which can, if desired, be linked by connecting means 38 to be responsive to a given con-

dition in the output stage 11, as will be described. So that the pistons can yield to the right under certain conditions, also described below, means 39 such as an accumulator, pressure relief valve, or the like, can be provided. The extremes of motion of the piston 17 and, it follows of the piston assembly 16, can be controlled by stop means 40 and 41 at opposite ends of the cylinder 18. If desired, as best seen in Figure 1, these stop means can be coupled through suitable connecting means 40a and 41a, either electrical or mechanical, to the output and input stages 11 and 10, respectively, for purposes of either terminating the inflow or stopping the operation of the output stage when the piston 17 reaches an extreme.

In operation, assuming the coupled pistons 16 and 17 are disposed somewhere between their extremes of motion, a continuous supply of fluid material is introduced through the pipe 22 to fill the rod 19 to the left of the seals 25, the toroidal space 31, the cylinder 13, the crystallizing body 14, and the mouth 15, to the output stage 11, which will be assumed to comprise a packaging machine which draws material intermittently. With fluid pressure applied to the piston 17 to urge the piston assembly 16 to the left under a predetermined force, and with a continuous inflow of material under pressure into the pipe 22, the piston assembly 16 will move to the left at such times as the output stage 11 is drawing material and will move to the right when it is not. While normally, it would be expected that the piston assembly 16 would shift to and fro over a more or less constant short range, in the event of a momentary increase in inflow through the pipe 22 the system can continue to operate without exceeding critical pressure limitations at the output within the limits of the total capacity of the cylinder 13. Similarly, a reduction of inflow will not reduce the internal pressures critically or terminate the operation of the system within the limits of the quantity of material stored in the cylinder 13 to the left of the piston assembly 16. It follows that the output stage 11 can in a like manner introduce variations in its demand over the same limits without exceeding established pressure parameters throughout the system. If, however, either extreme position is reached for the piston, the system can be stopped automatically through the connections 40a and 41a.

If the output of the continuously operating output stage 11 is wholly independent of the counter-pressure in the coupling unit 12, the movable pistons can be maintained under a continuous bias via the fluid introduced into the opening 35 from the source 36. If this output is sensitive to the counter-pressure in the unit or if it is desirable to exert discharging pressure on the material in the unit only during the periods when the material is being drawn by the intermittently operating output stage 11, the pressure on the piston 17 can be controlled through the connecting means 38 in such a way that it is under working pressure only during the time the material is being taken by the output stage, the pressure being relieved when no substance is being taken.

It will be understood that the novel functions achieved by the representative apparatus of Figure 2 can in accordance with the invention be attained by various modifications thereof. Thus, referring to Figure 3, there is illustrated a connecting unit 12' similar in many ways to the unit 12 of Figure 1 and like parts of which are identified by like primed reference characters. The unit 12' differs from the unit 12 in its mode of introduction of fluid material. Received in cylinder 13' is a piston assembly indicated generally by the numeral 42 coupled by a connecting rod 43 to yieldable driving means in the form of a piston 44 received in a cylinder 18'. The piston 44, and hence the piston assembly 42, are urged to the left by means of fluid pressure introduced by a suitable opening 35' in the end piece 21' of the cylinder 18'. Material is introduced through a variable coupling includ-

ing a fixed pipe 45 carried by a housing 46 and adapted to be connected through valve means 47 to a continuously operating infeed source such as a Votator, for example. The opposite or free end of the pipe 45 carries a gland fitting 48 which slidably receives in fluid tight relationship, the free end of a second pipe 49 the outside diameter of which is such that it can be received within the pipe 45 in telescoping fashion. The second and smaller pipe 49 is secured to the piston assembly 42 to connect with the cylinder 13' to the left of the piston assembly 42 via ducts 50, 51 and 52, a central opening 53 and a perforated face plate 54 which distributes the substance over the entire cross section of the cylinder 13'.

The operation of the coupling unit 12' is generally similar to that of the unit 12 as described above, with the piston assembly 42 seeking positions within the cylinder 13' which are a function of the supply and demand of the material to and from the unit. If desired, the crystallizing body 14' (and also the body 14) can be encased in a suitable heat transfer jacket 55. In the case of margarine manufacture, for example, the heat transfer jacket 55 can be used to heat the product to prevent stiffening through those intervals in which the flow is reduced or terminated. Emptying and cleaning of the crystallizing body 14' can be accomplished through a valved conduit 56.

When the units are operated as part of a margarine producing system, it will be understood that by suitable dimensioning of the parts, a separate crystallizing vessel or body can be dispensed with. In order that the margarine, at any position of the movable piston, stays in the unit long enough to attain the desired consistency, the content of the connecting unit not covered by the strokes of the piston assemblies 16 or 42 (Figures 2 and 3, respectively) to their left should be at least equal to Qt in which Q represents yield per unit of time of the continuously operating feed device and t the time needed to obtain the desired consistency.

It will be understood, therefore, that various modifications can be made within the scope of the present invention which should not be regarded as limited except as defined by the following claims.

I claim:

45. 1. Apparatus for delivering quantities of viscous substance intermittently comprising a continuously operating input stage to furnish a substantially continuous flow of substance, an intermittently operating output stage to receive and deliver quantities of the substance intermittently, and an intermediate compensating unit including a chamber, a first piston movable in the chamber to vary the capacity thereof, first conduit means connecting the end of the chamber opposite the piston to the output stage, second conduit means connecting the continuously operating input stage to the chamber through the piston, yieldable drive means continuously urging the first piston to reduce the chamber capacity with a predetermined force including a second piston and a cylinder, means to introduce fluid pressure into the cylinder, and connecting means between the first and second pistons comprising a hollow tube between the pistons and communicating with the chamber through the piston movable therein, said second conduit means comprising said hollow tube and a second tube communicating with the input stage telescopically slidably received in the hollow tube and passing through the second piston in sliding fluid-tight relationship.

70. 2. Apparatus for delivering quantities of viscous substance intermittently comprising a continuously operating input stage to furnish a substantially continuous flow of substance, an intermittently operating output stage to receive and deliver quantities of the substance intermittently, and an intermediate compensating unit including an enclosure forming a chamber, a piston movable in the chamber to vary the capacity thereof including an

aperture of small cross-sectional area with respect to the area of the front face of the piston passing through the piston at a location spaced inwardly from the periphery of the piston, first conduit means connecting the end of the chamber opposite the piston to the output stage, second conduit means connecting the continuously operating input stage to the chamber through the piston aperture, yieldable drive means continuously urging the piston to reduce the chamber capacity with a predetermined force, and guide means mounted in front of the front face of the piston and extending outwardly substantially from the piston aperture substantially close to the inner surface of the enclosure forming the chamber to spread the viscous material outwardly from the aperture about the inner surface as it passes into the chamber, thereby distributing the material over the entire cross-section of the chamber.

3. Apparatus according to claim 2 wherein said guide means includes a perforated plate adjacent to the front face of the piston.

4. Apparatus according to claim 2 wherein the guide means has a convexly conical face cooperating with the front face of the piston and extending outwardly to a location adjacent to the interior surface of the enclosure forming the chamber to provide a passage extending between the front face of the piston and the conical face of the guide means which communicates with the chamber about the periphery of the guide means and adjacent to the interior surface of the enclosure, whereby the flowing material is distributed evenly over the cross-section of the chamber.

5. Apparatus according to claim 4 wherein the piston has a concave front face and including distance means to space the conical face of the guide means from the piston face to form a toroidal space communicating with the chamber about the periphery of the guide means at a location adjacent to the inner surface of the enclosure forming the chamber and communicating with the second conduit means through the piston aperture.

6. Apparatus according to claim 2 wherein the coupling device includes a crystallizing chamber between the piston and the output stage.

7. An arrangement for coupling a supply device for continuously supplying a flowable substance under pressure to an accepting device which intermittently accepts a quantity of such substance, this arrangement consisting of a connecting conduit between the outlet of the supply device and the inlet of the accepting device, a piston movable within said connecting conduit so as to alter the capacity thereof and having an aperture in its head of small cross-sectional area with respect to the connecting conduit and spaced inwardly from the periphery of the piston, a second conduit connecting the supply device to the connecting conduit through the piston aperture through which the substance from the supply device passes to the accepting device, and guide means mounted

in front of the front face of the piston and extending outwardly substantially from the piston aperture substantially close to the inner surface of the connecting conduit to spread the flowable substance outwardly from the aperture about the inner surface as it passes into the connecting conduit, thereby distributing the material over the entire cross-section of the connecting conduit.

5 8. Apparatus according to claim 7 wherein the guide means includes a perforated plate secured to the piston and adjacent to the front face of the piston for distributing the flowable substance from the aperture.

10 9. Apparatus according to claim 7 wherein the guide means includes a double convex cone structure secured to the piston and adjacent to the front face of the piston providing an annular passageway leading outwardly from the piston aperture to a location adjacent to the inner surface of the connecting conduit for distributing the flowable substance from the aperture.

15 10. An arrangement for coupling a supply device for continuously supplying a flowable substance under pressure to an accepting device which intermittently accepts a quantity of such substance, this arrangement consisting of a first conduit, a first piston movable within said first conduit so as to alter the capacity thereof and having an aperture extending through it, a second conduit, a second piston movable in said second conduit and having a passage extending through it, a first tube secured to said first and second pistons to provide a mechanical connection between said first and said pistons and communicating with the first conduit through the first piston aperture, a second tube fixed relative to the second conduit and passing into the first tube and communicating with the supply device, whereby substance from the supply device passes through the second tube, the first tube, 20 and the aperture in the first piston into the first conduit, fluid pressure means connected to said second conduit for actuating the second piston to urge the first piston to reduce the capacity of the first conduit, the second conduit on the side of the second piston not in contact with the fluid pressure being open to the atmosphere.
